[57] CLAIM

The ornamental design for spring loaded chop sticks, as shown and described.

DESCRIPTION

FIG. 1 is a top plan view of spring loaded chop sticks showing my new design;

FIG. 2 is a side elevational view thereof;

FIG. 3 is a bottom plan view thereof;

FIG. 4 is a left end view thereof;

FIG. 5 is a right end view thereof;

FIG. 6 is a transverse sectional elevational view taken along line 6—6 of FIG. 2;

FIG. 7 is a top plan view of an alternate embodiment of the design for spring loaded chop sticks;

FIG. 8 is a side elevational view thereof;

FIG. 9 is a bottom plan view thereof;

FIG. 10 is a left end view thereof;

FIG. 11 is a right end view thereof; and

FIG. 12 is a transverse sectional elevational view thereof taken along line 12—12 of FIG. 8.

The side elevations not shown are mirror images of the side elevations shown for each embodiment.

FIG. 1.

FIG. 2.

FIG. 3.

FIG. 4.

FIG. 6.

FIG. 5.

FIG. 7.

FIG. 8.

FIG. 9.

FIG. 10.

FIG. 12.

FIG. 11.
